PULL

Sigfred P. Kjellgren, % Amerock Corporation,
4000 Auburn St., Rockford, Ill.

Filed May 16, 1960, Ser. No. 60,606

Term of patent 14 years

(Cl. D10—8)

Fig. 2 is a plan view.

Fig. 3 is a side view of the pull.

Fig. 4 is an enlarged sectional view taken along the line 4—4 in Fig. 1.

I claim:

The ornamental design for a pull, substantially as shown.
